UNITED STATES PATENT OFFICE.

WALDEMAR KOPS, OF NEW YORK, N. Y., ASSIGNOR TO KOPS BROS. INC., OF NEW YORK,
N. Y., A CORPORATION OF NEW YORK.

APPAREL GARMENT.

Application filed June 11, 1924. Serial No. 719,293.

My present invention relates to an apparel garment and more particularly to a corset in which tension straps for supporting the abdomen and self-reducing straps for shaping the abdominal region of the wearer are employed. I am aware that heretofore abdominal tension straps and self-reducing straps have been embodied in apparel corsets. In these structures, however, the corsets in which these devices have been employed are open back corsets in which the adjustment of the garment to position on the body of the wearer has been effected by lacing the garment at the back thereof. In this adjustment of the corset garments as so constructed it is necessary for those portions of the garment overlying the back of the body below the waistline and surrounding the buttocks and thighs of the wearer to first assume a fixed position and then the self-reducing straps and the tension straps are adjusted to place. This obviously results in the necessity of the production of a relatively large number of types of these garments in order to properly comply with the conditions which must necessarily be met in individual cases in supplying these garments as to cause the tension straps and self-reducing straps to assume their proper places to perform their intended functions these straps must be placed so as to assume relatively different positions in different garments.

The object of my present invention is to overcome this difficulty and inconvenience in supplying and fitting garments in individual cases making it unnecessary to make and carry so many different types of garments inasmuch as the garment made in accordance with my invention may be shifted to a greater or lesser extent after the same is placed on the body in order to bring the tension straps and self-reducing straps to their required positions to enable them to perform their intended functions properly.

In carrying out the invention the same is incorporated in a closed back garment in which there are elastic sections preferably placed in positions forward of the axillary line of the garment and in the outer front portions of the garment self-reducing straps are employed and on the inner side of the garment and between the self-reducing straps and the outer portion of the front of the garment abdominal tension straps are employed whereby, as will be hereinafter more par-

ticularly described, the self-reducing straps coacting with the elastic sections of the garment reduce and confine the abdominal sections of the body of the wearer and the tension straps which in part at least are also preferably made of elastic material coacting with the elastic sections of the garment produce a double yielding effect in supporting the abdomen of the wearer and the adjacent portions of these tension and self-reducing straps coact with one another in producing the functions intended to be performed by each strap separately.

In the drawing:

Fig. 1 is a perspective view illustrating the use of the apparel garment made in accordance with my present invention.

Fig. 2 is plan looking at the garment from the inside thereof and in a flattened position, and

Fig. 3 is a section on line 3—3, Fig. 2.

By reference to the drawing, it will be seen that the apparel garment made in accordance with this invention preferably comprises front sections 10 and 11 fitted with the usual front steels 12 and 13 to which there are connected the customary clasps for connecting the front edges of the garment for securing the same in position on the body of the wearer. The front sections of the garment also include depending skirt members as indicated at 14 and 15. The skirt member 14 immediately below the front steel 12 may be provided with a hook 16 and the forward edge of the skirt section 15 immediately below the front steel 13 may be fitted with an eye member 17 to be engaged by the hook 16, and the lower front portions of these skirt sections as illustrated are provided with series of eyelets 18 and 19 through 25 which is threaded a lace as indicated in Fig. 1 of the drawing for suitably connecting the front portions of the skirt members of the garment.

The front sections of the garment also include elastic fabric members 20 and 21 which extend from the upper to the lower edges of the garment. The back section of the garment is indicated at 22 and as illustrated the front sections of the garment may be fitted with suitable stays 23 and 24 and the back section of the garment with suitable stays 25 and 26.

The front sections of the garment are similarly constructed and both of them are

provided with self-reducing straps and also with abdominal tension straps. The self-reducing strap in the right hand side of the garment is indicated at 27. At the forward end this self-reducing strap is connected adjacent the lower end of the front steel 12 by a line of stitching indicated at 28. The opposite or rearward edge of the self-reducing strap 27 is connected to the front section 10 along the adjacent edge of the elastic member 20 by a line of stitching indicated at 29. The upper edge of the self-reducing strap is connected to the front member along a line of stitching indicated at 30. 15 Otherwise than as stated, this self-reducing strap is free from the front member. A hose supporter strap 31 is connected at one end to the lower edge of the skirt section 14 preferably in alignment with the downwardly extending portion or extension of the self-reducing strap as indicated at 32. At its opposite end this hose supporter strap is connected to the extremity of the extension of the self-reducing strap as indicated at 33.

The hose supporter strap 31 is in the form of a loop of elastic material on which the clasp for engaging the hose is slidably mounted.

30 In this front portion of the garment I also employ an abdominal tension strap. As illustrated this is preferably made of an inelastic section 34 and an elastic section 35, the parts of which are connected to one another along the line indicated at 36. The inelastic section 34 of this tension strap is connected along one edge to the adjacent edge of the back section of the garment as indicated at 37 and the forward end of the elastic section 35 of the tension strap is connected to the forward part of the front section as indicated at 38, this connection being substantially along the same line of stitching 28 which secures the forward end of the self-reducing strap in place in the garment. 45 Immediately forward of the elastic member 20 and underlying the adjacent portion of the rearward end of the self-reducing strap an opening 39 is provided in the front member for the passage of a tension strap so that the major part of the inelastic section 34 of the tension strap underlies the elastic member 20 and the forward end of this inelastic section passes through the opening 39, while the elastic section 35 of the tension strap lies between the self-reducing strap and the underlying adjacent portion of the front section of the garment.

60 As hereinbefore stated, the construction in the other side of the garment is similar to that hereinbefore described. In the left hand side of the garment the self-reducing strap is indicated at 40. The forward end of the self-reducing strap is secured in the garment along a line of stitching 41 and the

70 rearward end along a line of stitching 42, while the upper edge of the self-reducing strap is connected to the front section of the garment along a line of stitching as indicated at 43. A hose supporter strap 44 is connected at one end to the lower edge of the skirt 15 as indicated at 45 while the opposite end of this hose supporter strap is connected to the lower extremity of the extension of the self-reducing strap 40 as indicated at 46. The hose supporter strap 44 is the counterpart of the hose supporter strap 31. In this forward portion of the garment the abdominal tension strap also comprises an inelastic section 47 and an elastic section 48 connected along their adjacent edges by a line indicated at 49. One edge of the inelastic section 47 of the tension strap is connected to the garment along a line of stitching 50 which also preferably connects the rearward edge of the elastic member 21 to the adjacent portion of the closed back member of the garment. The forward edge of the elastic section 48 of this tension strap is connected to the forward portion of the garment along a line indicated at 51. This is preferably coincident with the line of stitching 41 by which the forward edge of the self-reducing strap 40 is connected in the front section of the garment. The abdominal tension strap in this section of the garment extends through an opening 52 provided therefor immediately forward of the elastic member 21 and beneath the rearward edge of the self-reducing strap 40 so that the inelastic section 47 of this tension strap underlies a portion of the elastic member 21 and extends through the opening 52 while the elastic section of the tension strap underlies the self-reducing strap 40 and extends between the same and the adjacent underlying portion of the front section of the garment.

75 In the back member of the garment I may employ hose supporter straps 53 and 54 which are secured in similar positions on opposite sides of the central line of the back member along lines of stitching 55 and 56 substantially at the lower end of the body portion proper of the garment so that these 80 hose supporter straps 53 and 54 overlie the skirt sections 57 and 58 at the back of the garment, and connected to these hose supporter straps 53 and 54 are suitable hose supporters as indicated at 59 and 60. The lower front portions of the garment may also be provided with hose supporters indicated at 61 and 62.

85 It will now be understood that due to the elastic members of the garment which extend from the upper to the lower edges thereof and are preferably placed immediately forward of the axillary lines of the garment, the garment after being placed on the body may be readily shifted to the proper 90

position to cause the self-reducing straps and the abdominal tension straps to assume their proper places against the body of the wearer, and that the self-reducing straps 5 will function to mold the flesh of the wearer to the desired form and the tension straps to support the lower portions of the abdomen, and furthermore that due to the elastic sections of the garment and also to the elastic 10 sections of the tension straps there will be a double yielding effect produced in the support of the lower portion of the abdomen.

I claim as my invention:

15 1. In a corset, a closed back member, elastic side members, front members, means for connecting the edges of the front members for securing the corset in position on the body, tension straps each connected at its 20 forward end adjacent the forward edge of a front member extending over the outer surface of the said front member and passing through a slit provided therefor with the inner end portion thereof underlying the 25 adjacent portion of the corresponding elastic side member and attached at its inner end to the adjacent edge of the back member, and self reducing straps each connected to a front member and adapted to overlie 30 the portion of the tension strap extending across the said front member and to cooperate therewith by the tension applied thereto in shaping and supporting the abdomen of the wearer.

35 2. In a corset, a closed back member, elas-

tic side members extending from the upper to the lower edges of the garment, front members, front steel sections secured in the edges of the front members and adapted for fixing the garment in position on the wearer, 40 an inelastic self reducing strap associated with each front member, being connected at its forward edge adjacent the free edge of the front member and at its rearward edge adjacent the rearward edge of the front 45 member and having a downwardly extending portion free from the front member, and tension straps each associated with a front member and the self reducing strap 50 associated therewith, each tension strap comprising a forward elastic section connected at its forward end to the front member adjacent the forward edge thereof and lying between the front member and its self reducing strap, and a rearward inelastic section 55 extending through a slit in the front member adjacent the rearward end thereof and underlying the adjacent portion of the corresponding elastic side member and at its rearward edge connected to the adjacent 60 edge of the back member, the said self reducing straps and tension straps being adapted to cooperate with each other and with the front sections of the garment to shape and support the abdomen of the 65 wearer and to obviate the wrinkling of the garment in the parts in which these members are placed.

Signed by me this 6th day of June, 1924.

WALDEMAR KOPS.
